(57) **CLAIM**

The ornamental design for an electronic device case, as shown and described.

DESCRIPTION

FIG. 1 is a front perspective view of the electronic device case;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof;

FIG. 7 is a bottom plan view thereof;

FIG. 8 is a front perspective view of an alternative embodiment of the electronic device case;

FIG. 9 is a front elevation view thereof;

FIG. 10 is a rear elevation view thereof;

FIG. 11 is a left elevation view thereof;

FIG. 12 is a right elevation view thereof;

FIG. 13 is a top plan view thereof; and,

FIG. 14 is a bottom plan view thereof.

The broken showing of an electronic device case is included for the purpose of illustrating environment and forms no part of the claimed design.
